JOHN T. EWAN AND JAMES R. GLENN, OF HILLSBORO, ILLINOIS.

Letters Patent No. 79,218, dated June 23, 1868.

IMPROVEMENT IN SMUT-MILLS.

The Schedule referred to in these Letters Patent and making part of the same.

TO ALL WHOM IT MAY CONCERN:

Be it known that we, JOHN T. EWAN and JAMES R. GLENN, of Hillsboro, in the county of Montgomery, and in the State of Illinois, have invented certain new and useful Improvements in Combined Grain-Scourer, Polisher, Smut-Mill, and Separator; and do hereby declare that the following is a full, clear, and exact description thereof, reference being made to the accompanying drawings, and to the letters of reference marked thereon.

In the annexed drawings forming part of this specification, A represents a wooden frame, upon which the whole machine rests. It is so arranged that it can be turned at any angle that may be desired, for placing the belt on the driving-pulley B, which is at the bottom of the upright shaft C. This shaft goes up through the cylinder F, air-trunk D, and drum E.

The grain is poured into a hole in the top plate G of the cylinder, on to an inside top plate H, where it is equally scattered on all sides of the cylinder; then passing down between inside jacket and steel files I, where it is scoured; then down to the spring-steel wire or spring-brass wires J, where it is polished.

These spring-steel or spring-brass wires are placed on staves or boards, which are lined on back and front with sheet iron. The holes in the staves are bored through, a heavy wire placed across the holes, and the wires which form the brush are put in from the back and across this wire which holds them from pulling out. The sheet iron on the back keeps from going back as the grain presses on them, and the iron on front protects the stave from wear.

After the wheat is scoured and polished, it passes out of the cylinder on opposite sides into the suction-legs K K, where the chaff and all other light substances are separated from the wheat, the chaff and other light trash passing up the suction-legs, until they come to the top, where they are carried across, striking the check-board L, in the centre of the vacuum M, then turning down, the chaff falling into the lower end of the vacuum and out, the other light substances passing round and out through the air-trunk D and drum E, into exhaust-pipe N, where they leave the machine or mill. When the dust is scoured and polished from the grain, it passes between the inside and outside jacket, through holes in the bottom plate, into the dust-chamber O, where a small fan keeps it stirred, that the suction-fan P on top can lift it through the small-spouts S, running from the dust-chamber to the suction-legs. These spouts enter the suction-legs about two-thirds of the way up.

The valves R in the air-trunk D, just below the drum E, regulate the draught on the suction-legs. The inside and scouring-jackets are in halves, and held together with wooden ribs. The whole mill is held together with four iron rods passing through top and bottom plates, the jacket and scouring-apparatus resting on the bottom plate and supporting the top plate.

The steel files I I, which are used in scouring the grain, are cut on the same principle as a common file, and hardened in the same manner, to make them durable, giving the scourer a keen, fine scouring-surface.

We are aware that the devices herein described, taken separately, are of themselves not new; but

What we claim, is—

The arrangement, upon the frame A, in the manner described, of the suction-legs K K, chambers M M, check-boards L L, air-trunk D, and its valves R R, dust-chamber O, and spouts S S, with the cylinder F, its wire brushes J, staves I, plates G H, fan P, and shaft C, with their various parts, all constructed and operating substantially as and for the purposes set forth.

In testimony that we claim the foregoing, we have hereunto set our hands, this 2d day of April, 1868.

JOHN T. EWAN,
JAMES R. GLENN.
